UNITED STATES PATENT OFFICE.

WILLIAM V. BULMAN, OF PHILADELPHIA, PENNSYLVANIA.

ADJUSTABLE SUPPORTING CHAIR FOR WALL CLOSETS, ETC.

Application filed May 1, 1928. Serial No. 274,212.

This invention is a novel adjustable supporting chair for wall closet bowls and the like, and the principal object of the invention is to provide a novel support casting for wall 5 closet bowls adapted to be built up from the flooring and contained within and forming a utility opening in the wall in the rear of the closet, the supporting chair being made in three members, one of which is embedded 10 in the floor as a base, and has a socket extending slightly above the floor and within a utility opening in said wall. The second member has a tongue portion vertically adjustably engaging the socket in the first member, and having a head portion having a horizontal bore and adapted to fit within the utility opening flush with the terra-cotta brick, or other non-finished foundation of the wall, said second member being tiltable 15 20 on the first member so as to "true" or plumb the second member. The third member comprises a plate casting having a tubular caulking hub adjustably mounted in the bore of the second member, the plate having means 25 for securing the closet bowl thereto, and means for adjusting the plate flush with the surface of the usual marble or tile "finish" of the wall which marble or tile is cut out around the plate; furthermore, the third member is 30 adjustable universally of, and towards or away from, the second member.

Another object is to provide a novel caulking connection for securing the soil pipe to the tubular outlet on the third member of the 35 supporting chair.

A further object is to provide an adjustable support which will enable proper pipe connections to the bowl, such as the soil pipe, and water supply pipe, to be made from the rear 40 of the wall after the bowl is mounted in place, all connections being readily accessible at all times through the utility opening without having to take down the bowl, or tear down the wall.

I will explain the invention with reference 45 to the accompanying drawings which illustrate one practical embodiment thereof to enable others to adopt and use the same; and will summarize in the claims the novel features of construction, and novel combinations of parts, for which protection is desired.

In said drawings:

Figure 1 is a vertical section through the 50 wall, floor, support and utility chamber, showing the bowl in attached position.

Figure 2 is a front elevation of the members, detached.

Figure 3 is a rear elevation of the members, detached.

Figure 4 is a top plan view of the first member, detached.

Figure 5 is a rear perspective view of the third member of the support, detached.

As shown, the supporting chair comprises a cast iron base plate 1 adapted to rest upon the rough foundation A (Fig. 1) of the floor, 60 said plate 1 having an upstanding rectangular socket 1^a formed integrally therewith, adjacent one end, said socket being open at the top but closed at the bottom, and suitable 70 strengthening ribs 1^b, 1^c connect the walls of the socket 1^a with plate 1. Plate 1 may be cut away as at 1^d and 1^e for the purpose of saving unnecessary material and weight. 75 Socket portion 1^a is preferably made of sufficient height to extend above the finished floor line A' (Fig. 1) (which line A' is usually about four inches above the rough foundation A) of the tile or marble "finish" usually used in toilets, bathrooms, etc.; the "finish" of the floor covering up the plate 1 and lower part of ribs 1^b.

Socket portion 1^a is disposed vertically below the rough foundation C of the wall upon which the closet bowl B is to be mounted, and disposed in a utility opening in said wall C, and the plate 1 extends out into the room directly below the said bowl in order to obtain proper balance for the bowl B. The front or outer face of the socket 1^a is preferably disposed substantially flush with a terra-cotta or brick wall foundation C over which is usually cemented a marble or other finish C' for the face of the wall. 90

The second member of the supporting chair 95 comprises a cast head plate 2 substantially rectangular in shape with suitable top and side flanges 2^a, 2^b, and having its two upper corners boxed as at 2^c for the passage therethrough of the bolts which secure the closet bowl B thereto. In plate 2 is a circular opening bounded by an annular flange 2^d connected at each side by spaced webs 2^e and 2^f, to the side flanges 2^b; and a portion between the flanges 2^e, 2^f adjacent annular flange 2^d is 100 boxed in as at 2^g, for the passage of the bolts which secure the closet bowl thereto. A lightening hole 2^h is preferably formed in plate 2 above the annular flange 2^d.

The plate 2 is narrowed down as at 2^k be- 110

low the ring 2^d to suit the width of the socket 1^a of base 1, and the reduced portion 2^k is provided with side flanges 2^m extended to meet the flange 2^d . Flanges 2^m are of width 6 to suit the corresponding dimension of the socket 1^a into which the lower end 2^k of plate 2 enters. At the lower end of plate 2^k at each side are tapped lugs 2^n (Fig. 1) through which set screws 2^p extend projecting below 10 said plate 2^k , the lower ends of the screws 2^p being reduced as at 2^q and entering perforations 1^b in the base 1, whereby adjustment of the two screws 2^p will raise or lower their respective sides of the head casting in socket 15 1^a to effect proper adjustment for height and plumb. A set screw 1^k in the front face of socket 1^a engaging the portion 2^k holds the head casting in erect position.

Portion 2^k of plate 2 is preferably offset 20 below ring 2^d behind the plane of plate 2 a distance equal to the thickness of the front wall of socket 1^a so that the plane of plate 2 will include the front face of socket 1^a when assembled and adjusted flush with the front 25 face of the rough foundation C of the wall, which foundation C is usually built right up to width of the head casting 2. When head casting 2 has been properly adjusted by set screws 2^p and 1^k , concrete may be poured into 30 the socket 1^a from the rear side to fixedly secure the two parts.

When the bowl B is of the air vent type it is necessary to leave an opening through foundation C above the top of head casting 35 2, which may be conveniently done by screwing a bowed metallic strip 3 over the upper end of the casting 2, and the terra-cotta or brick foundation C can then be completed over this strip 3 and down each side of the 40 casting 2 to meet the floor line A maintaining the utility opening in the wall the same width as the overall width of said casting 2.

The third member of the supporting chair comprises a plate 4 of general shape and dimensions to suit the back of the particular bowl B which is to be mounted thereon, the plate 4 being cut away at its top, as at 4^a , below the upper edge of the air vent outlet B' of said bowl. At the rear side of plate 4 is 45 a tubular caulking hub 4^b adapted to extend through the annular ring 2^d in casting 2. Within the ring 2^d of casting 2 is an annular lip 2^x adapted to loosely engage the exterior of caulking hub 4^b to permit slight universal 50 adjustment, the main portion of annular ring 2^d being somewhat larger in diameter than that of hub 4^b . Extending radially into the bore 2^d , spaced approximately 90° apart, are set screws 2^y for locking the hub 4^b in bore 2^d 55 after adjustment, the lip 2^x largely taking the weight of plate 4 and the bowl B mounted thereon.

Coaxial with and disposed within the caulking hub 4^b is a shorter and smaller tubular extension 4^e adapted to fit within the end 60

of soil pipe S as shown in Fig. 1 for the purpose of making a caulked connection between the soil pipe S and the plate 4, when adjusted, said plate being cut away as at 4^a in way of tubular extension 4^e . After adjustment of 70 plate 4 (as hereinafter explained) okum 4^e is forced in between the hub 4^b and the soil pipe S from the rear end of said hub towards the plate 4, and the outer portion of the joint is caulked with lead or the like 4^f to complete the watertight connection. On the front face of plate 4 concentric with opening 4^a is an annular raised ring 4^g adapted to engage a rubber gasket B^2 in an annular recess B^3 in the back face of bowl B around the soil 80 outlet of the bowl for the purpose of making a watertight joint between the bowl and outlet of plate 4.

The bowl B is bolted through plate 4 by means of four bolts 4^h , passing through sleeves 4^i (Fig. 1) and engaging tapped bores in the box portions 2^c (or 2^b) in the rear of casting 2, the bolts 4^h loosely passing through said sleeves 4^i and also through perforations in plate 4.

Sleeves 4^i are provided with heads 4^k engaging the plate 4, and said sleeves are threaded into the tapped bores in the adjacent face of plate 2, and since one such sleeve 4^i (and bolt) is disposed adjacent each corner of plate 4 by adjusting the threaded sleeves before set screws 2^y are tightened plate 4 can be adjusted universally of casting 2 with great accuracy flush with the plane of the marble or other facing C' of the wall, the marble finish C' being worked up to the sides and bottom edges of plate 4, but at the top conforming substantially with the curvature of strip 3 in the wall foundation C where the bowl B is of the air vent type. Where, however, the bowl is not of the air vent type the marble C' may be worked to the shape of plate 4, or at least slightly overlapping the area of the back face of bowl B.

The water supply pipe W may be connected in the usual manner to the water inlet of the bowl through the utility opening under strip 3, and in fact all connections, adjustments, and caulking may readily be effected through the utility opening even after the bowl B is initially set in place on the chair.

Casting 2 is vertically adjustable in socket 1^a and also tiltable forwardly and backwardly in the socket as well as vertically in its own plane; and plate 4 is universally adjustable 120 on casting 2, as well as towards or from the casting 2, said construction permitting a wide range of adjustments in order to properly place or set the bowl with respect to the lines of finish of the floor and wall.

I do not limit my invention to the exact form shown in the drawings, for obviously changes may be made therein within the scope of the claims.

I claim:—

1. A supporting chair for wall closets and the like, comprising a casting adapted to be mounted in the wall and having a horizontal bore; and a plate adjustably mounted on said casting and having a tubular caulking hub engaging the bore; means for securing the closet to said plate; and means for connecting the caulking hub to the outlet of said closet.
2. In a supporting chair as set forth in claim 1, said closet securing means comprising bolts passing through the closet and plate and engaging tapped bores in the casting; and sleeves around said bolts interposed between the casting and plate, said sleeves being threaded into the casting.
3. In a supporting chair as set forth in claim 1, an annular lip in said bore loosely engaging the caulking hub; and spaced radially disposed set screws entering said bore and engaging said hub.
4. In a supporting chair as set forth in claim 1, said caulking hub being adapted to receive the end of a soil pipe; a tubular member on said plate within the hub and adapted to fit within the soil pipe; said plate having an outlet opening therethrough into the tubular member; and an annular flange on the outer face of said plate surrounding the opening.
5. In a supporting chair as set forth in claim 1, said closet having an air vent; a bowed strip over the upper end of the casting for forming an opening through the wall; and the upper end of the plate being cut away between the outlet of the air vent and said openings.
6. A supporting chair for wall closets and the like, comprising a base casting adapted to be embedded in the floor, a head casting adjustably mounted on said base within a utility opening in the wall, and having a horizontal bore, and a plate adjustably mounted on said head casting and having a tubular caulking hub engaging the bore; means for securing the closet to said plate; and means for connecting the caulking hub to the outlet of said closet.
7. In a supporting chair as set forth in claim 6, said closet securing means comprising bolts passing through the closet and plate and engaging tapped bores in the head casting; and sleeves around said bolts interposed between the head casting and plate, said sleeves being threaded into the head casting.
8. In a supporting chair as set forth in claim 6, an annular lip at one end of said bore loosely engaging the caulking hub; and spaced radially disposed set screws entering said bore and engaging the hub.
9. In a supporting chair as set forth in claim 6, said caulking hub being adapted to receive the end of a soil pipe; a tubular member on said plate within the hub and adapted to fit within the soil pipe; said plate having an outlet opening therethrough into the tubular member; and an annular flange on the outer face of said plate surrounding the opening.
10. In a supporting chair as set forth in claim 6, said closet having an air vent; a bowed strip secured over the upper end of the head casting for forming an opening through the wall; and the upper end of the plate being cut away between the outlet of the air vent and said opening.
11. A supporting chair for wall closets and the like, comprising a base casting adapted to be embedded in the floor adjacent a wall and having a vertical socket adapted to lie within a utility opening in said wall; a head casting adjustably mounted in said socket and disposed within said utility opening; said head casting having a horizontal bore; and a plate mounted on said head casting and adjustable to the finished surface of the wall; and having a tubular caulking hub engaging the bore; means for securing the closet to said plate; and means for connecting the caulking hub to the outlet of said closet.
12. In a supporting chair as set forth in claim 11, said closet securing means comprising bolts passing through the closet and plate and engaging tapped bores in the head casting; and sleeves around said bolts interposed between the head casting and plate, said sleeves being threaded into the head casting.
13. In a supporting chair as set forth in claim 11, an annular lip at one end of said bore loosely engaging the caulking hub; and spaced radially disposed set screws entering said bore and engaging the hub.
14. In a supporting chair as set forth in claim 1, said head casting having an extension at its lower end entering said socket; set screws projecting below each side of said extension and entering recesses in the lower end of said socket; and a set screw in the front face of said socket engaging the extension.
15. In a supporting chair as set forth in claim 11, said caulking hub being adapted to enclose the end of a soil pipe; a tubular member on said plate within the hub and adapted to fit within the soil pipe; said plate having an outlet opening therethrough into the tubular member; and an annular flange on the outer face of said plate surrounding the opening.
16. In a supporting chair as set forth in claim 11, said closet having an air vent; a bowed strip secured over the upper end of the head casting for enlarging the utility opening; and the upper end of the plate being cut away between the outlet of the air vent and said opening.
17. A supporting chair for wall closets and the like comprising a base casting adapted to underlie the closet and to be embedded in the floor adjacent the wall; said base having a vertical socket adapted to lie within a utility

opening in said wall; a head casting adjustably mounted in said socket and disposed within the utility opening flush with the body portion of said wall; said casting having a horizontal bore; and a plate adjustably mounted on said head casting and adjustable to the finished surface of the wall, and having a tubular caulking hub engaging the bore; means for securing the closet to said plate; and means for connecting the caulking hub to the outlet of said closet.

18. In a supporting chair as set forth in claim 17, said closet securing means comprising bolts passing through the closet and plate and engaging tapped bores in the head casting; and sleeves around said bolts interposed between the head casting and plate, said sleeves being threaded into the head casting.

19. In a supporting chair as set forth in claim 17, said caulking hub being adapted to 20 enclose the end of a soil pipe; a tubular member on said plate within the hub and adapted to fit within the soil pipe, said plate having an outlet opening therethrough into the tubular member; and an annular flange on the 25 outer face of said plate surrounding the opening.

20. In a supporting chair as set forth in claim 17, said closet having an air vent; a bowed strip secured over the upper end of 30 the head casting for enlarging the utility opening through the body of the wall; the upper end of the plate being cut away between the outlet of the air vent and said opening.

WILLIAM V. BULMAN.
